UNITED STATES PATENT OFFICE.

EDSON S. HINELINE, OF APPONAUG, RHODE ISLAND, ASSIGNOR TO HINELINE ENGINEERING COMPANY, OF PROVIDENCE, RHODE ISLAND, A CORPORATION OF RHODE ISLAND.

STOP MOTION FOR KNITTING MACHINES.

Application filed August 31, 1921. Serial No. 497,219.

To all whom it may concern:

Be it known that I, EDSON S. HINELINE, a citizen of the United States, and a resident of Apponaug, in the county of Kent 5 and State of Rhode Island, have invented an Improvement in Stop Motions for Knitting Machines, of which the following description, in connection with the accompanying drawings, is a specification, like characters on the drawings representing like parts.

This invention relates to stop motions for textile machines and particularly to electrical stop motions for knitting machines.

15 In order that the principle of the invention may be readily understood, I have disclosed certain embodiments thereof in the accompanying drawings, wherein—

Fig. 1 is a right hand elevation of an 20 electrical stop motion embodying my invention;

Fig. 2 is a side elevation of a part of the structure shown in Fig. 1;

Fig. 3 is a plan view of the part of the 25 structure shown in Fig. 1, the view being partly in transverse section;

Fig. 4 is a front elevation of a part of the structure shown in Fig. 1, the cover 30 of the box or receptacle for the magnet and other parts being removed;

Fig. 5 is a side elevation of the structure shown in Fig. 4;

Fig. 6 is a view similar to Fig. 4 of a 35 slightly modified form of my invention; and

Fig. 7 is a side elevation of the construction shown in Fig. 6.

The invention herein disclosed constitutes an improvement upon that shown in my 40 co-pending application Serial No. 365,939, filed March 15, 1920, and more particularly relates to the brake mechanism. Certain parts are shown which are common to this application and to said co-pending application, and which will not be described herein with great particularity.

The stop motion herein disclosed is readily applicable to knitting machines of various types. I have chosen to represent it 50 as applied to the so-called Banner machine of the type disclosed in the patent to Joshua D. Hemphill, No. 933,443, dated September 7, 1909, but obviously my invention is not restricted in its application thereto. It is

unnecessary to refer in detail to the knitting mechanism otherwise than to state that it is provided with a drive shaft s , whereon are positioned the loose pulley p^2 , the slow speed pulley p' and the quick speed pulley p . When the machine is running, the belt is held upon the pulley p by means of a belt guide 7 , shown most clearly in Fig. 1, and which extends from an arm 2 itself extending from a shipper frame or member 3 mounted for sliding movement 60 upon a suitable pin or stud 4 laterally extending from the frame or housing a of the machine.

Suitably mounted upon the framing of the machine is a rock shaft 5 having a 70 machine-running and machine-stopped position, said rock shaft desirably having an upwardly extending arm shown in Fig. 4 and adapted to take against one side of the shipper frame 3 .

Operatively connected to said arm is a spring 6 , the opposite end whereof is attached to the framing of the machine in such a way that the springs tend constantly to rock the shaft 5 from the machine-running to machine-stopped position, and at the same time to move the shipper with the belt guide into a position to place the belt upon the loose pulley p^2 .

In order to prevent all danger of fire 85 from arcing or sparking all the contacts are preferably placed in closed receptacles. I attach to the framing of the machine a box or receptacle indicated at 7 in Fig. 1, it having a cover removed in Figs. 4 and 90

6, so as to show the interior construction. The rock shaft 5 extends into the box 7 , being received in suitable bearings $8, 9$. Mounted upon said shaft 5 within the box 95 8 is an insulation member or ring 10 , to which is clamped or otherwise secured a metallic strip or clip 11 from which extends a lead wire 12 . Said strip or clip has two contact blades or parts $13, 14$ which are adapted when the shaft 5 is in the position shown in Fig. 4 to make contact with like parts or terminals $15, 16$ extending from a lead wire 17 .

The shaft 5 is provided with a cam or disk 18 fast thereon and having a radial notch adapted to be engaged by an armature 19 when the magnet 20 is de-energized. The armature is here shown as provided 105

with an upwardly extending projection 21 for this purpose.

So long as the magnet 20 remains de-
5 energized, the projection 21 from the ar-
mature engages with the said notch upon
the disk or cam 18, thereby preventing the
rock shaft 5 from turning. When, how-
ever, the magnet 20 is energized in any suit-
able manner and as herein disclosed by
10 either a broken thread or a thread having
a faulty or impaired tension (and specific-
ally though not necessarily by a thread
having undue tension), the armature is at-
tracted, withdrawing the projection 21 from
15 the projection upon the cam 18, thereby
permitting the shaft 5 to rock in a clock-
wise direction with the result that the belt
is shifted to the loose pulley p^2 .

The shaft 5 cannot be restored to the ma-
chine starting position until the break or de-
fective tension in the yarn is remedied, since
said magnet remains energized so far as
either defect continues, and therefore the
20 said projection cannot be brought into co-
acting relation to hold the rock shaft 5 in
machine-running position.

The mechanism of my invention is adapt-
ed to be secured to knitting machines of
30 general construction with no change in the
structure of such machine. The machine
herein illustrated is provided with an up-
wardly extending creel rod 22 shown broken
away in Fig. 1. Desirably the said creel rod
35 has a laterally extending bracket of the
character shown in my said co-pending ap-
plication, and directly supported upon said
lateral bracket is a box or receptacle 23,
shown most clearly in Figs. 1 and 2 and
40 having a cover 24. The said box or recep-
tacle is desirably provided with a series of
mercury cups, preferably four in number,
corresponding to the number of yarns. Lat-
erally extending from said box or receptacle
45 are hubs 25, here shown as four in num-
ber and receiving therein for rocking move-
ment shafts 26, which have upwardly ex-
tending therefrom and fast therewith grids
50 or members 27 having spaced fingers 28 be-
tween which and the fingers of a fixed mem-
ber 29, the thread is adapted to be placed,
and in such a manner that while the thread
55 remains unbroken, each corresponding mem-
ber 27 is held in upright position. In a
manner not herein necessary to describe in
detail, the downward movement of the mem-
ber 27 causes rocking movement of the cor-
60 responding rock shaft 26, and the making
of a contact within the box or receptacle 23
as disclosed in my said co-pending appli-
cation. Upwardly extending from said box
or receptacle 23, 24, is a rod supporting at
65 its upper end a head or block 30, here shown
as square, and upon the four sides of which
are pivoted levers 31, 31^a, 31^b, 31^c, each hav-
ing a forked outer end 32 adapted to receive

the thread passing upwardly from the pack-
ages through the members 27, 29, and there-
after downwardly to the knitting machine.
In the event of undue tension of a yarn or
70 thread, the respective lever 31, etc. is drawn
downwardly until the yarn slips out of the
forked end 32, thereby providing sufficient
slack to prevent breakage of the yarn, but
before this action occurs, the machine is
75 stopped through the following mechanism.

Each lever 31, etc. has pivoted thereto an
upright rod 33, the lower end of which
passes through the cover 24 of the receptacle
23 and is provided with an electrical contact
80 at its end adapted to make contact with the
mercury in the said cup 23. In this manner
the machine is adapted to be stopped in the
event either of yarn breakage or defect in
the tension of the yarn, and particularly in
85 the event of excessive tension.

I have provided means whereby the brake
is applied to the fast pulley immediately
90 upon the completion of the circuit in the
manner described and the energization of
the magnet 20. For this purpose I have in
Figs. 4 and 5 shown a cam 34 fast upon the
95 shaft 5 and adapted to engage a lever 35
pivoted at 36 and having an arm 37, itself
provided with a cam portion 38 and also
having a second arm 39 provided at its end
with a brake face 40 of suitable material
50 adapted to contact with a lateral face of the
fast pulley p .

When the machine is in running position
indicated in Figs. 4 and 5, the cam 34 oc-
100 cupies the position shown in Fig. 5 and holds
the brake out of contact with the pulley 5.
Immediately, however, upon the movement
of the shaft 5, the cam 34 is withdrawn from
105 engagement of the lever 35, and thereupon
the spring 41 acts to move the brake face 40
forcibly against the pulley p . The said
spring 40 is attached at one end 42 to said
lever arm 37 and at its opposite end is at-
tached to the frame of the machine.

It will be apparent that in this form of
my invention the lever 35 is pivoted at 36
110 upon a bracket 43 secured by bolts 44, or
otherwise, to the framing of the machine,
and that the brake face 40 is adapted to con-
tact with a lateral face of the pulley 5.

In Figs. 6 and 7, I have represented a
slightly modified form of my invention.
Therein the shaft has fast thereon a cam 45
upon which is adapted to ride a roll 46 car-
ried upon the arm 47 of a bell crank lever
120 pivoted at 48 between two upstanding ears
49 extending from a bracket 50, itself se-
cured by a pair of screws 51 directly to the
outer face of the box or casing 7. Desir-
ably said bracket 50 is of the right angled
125 form shown in Fig. 6, and is attached at a
corner of the box 7 to two of the faces
thereof.

The opposite arm 52 of the bell crank lever
130

has freely pivoted at its outer end at 53 a brake piece 54 having a suitable lining 55 adapted to contact with the peripheral edge of the quick pulley p , as indicated clearly 5 in said Figs. 6 and 7.

Secured to the end 56 of the bell crank lever arm 47 is a coiled spring 57, the opposite end whereof is attached to a pin 58 secured to the box or receptacle 7. Said 10 spring tends constantly to move the brake member 54, 55 into contact with the pulley p , such movement being prevented by the cam 47 so long as the shaft 5 is held from rotative movement by the de-energized magnet. It will be noted that the brake member 15 54 is pivoted for rocking movement at 53, so that it may conform in position to the periphery of the pulley p , so as to adjust itself thereto when applied. The brake herein 20 disclosed is so quick acting that it acts while the belt is still on the driving pulley, whether at high speed or at low speed. This is of importance because it causes stoppage of the moving parts before the broken end of the 25 yarn reaches the needles, and I have been enabled to reduce the height of the upright part indicated in Fig. 1, thus permitting an operative standing on the floor to rethread the mechanism conveniently.

Having thus described one illustrative embodiment of my invention, I desire it to be understood that although specific terms are employed, they are used in a generic and descriptive sense and not for purposes of 35 limitation, the scope of the invention being set forth in the following claims.

Claims—

1. Stopping mechanism for knitting machines comprising in combination, a rock 40 shaft having a disk, an electromagnet having an armature adapted to hold said disk from rotation until energized, means whereby yarn break or impaired tension effects energization of said magnet, a driving pulley, shipper means therefor, a brake adapted to be applied directly to said pulley, a lever carrying said brake, and a cam upon said rock shaft and controlling the movement of 45 said lever.

2. Electrical stopping means for knitting machines comprising in combination, a rock 50 shaft, a disk thereon, an electromagnet having an armature adapted when unenergized to hold said disk and shaft from rotation, 55 means whereby yarn breakage or undue tension effects energization of said magnet and permits rotation of said rock shaft, a driving pulley, a shipper therefor controlled by said rock shaft, a brake adapted to be applied directly against said driving pulley, a lever carrying said brake, and a cam upon 60 said rock shaft controlling said lever.

3. Stopping mechanism for knitting machines comprising, in combination, a shaft 65 having fast and loose pulleys thereon, a rock

shaft, a spring tending normally to move said rock shaft into machine stopping position, shipping means caused to function by rocking movement of said shaft, thread fault detecting means, and connections therefrom to restrain said rock shaft from rocking movement but permitting said shaft to rock upon the occurrence of thread fault, a cam upon the rock shaft, a bracket secured to the framing of the machine, a lever carried by said bracket and adapted to be directly acted upon by said cam to maintain a brake from braking position, and a brake upon said lever and adapted to engage said fast pulley. 70 75 80 85 90 95

4. Stopping mechanism for knitting machines comprising in combination, a shaft having fast and loose pulleys thereon, a rock shaft, a spring tending normally to move said rock shaft into machine stopping position, shipping means caused to function by rocking movement of said shaft, thread fault detecting means, connections therefrom to restrain said rock shaft from rocking movement, but permitting said shaft to rock upon the occurrence of thread fault, a cam on the rock shaft, a bracket secured to the framing of the machine, a lever carried by said bracket and adapted to be directly acted upon by said cam to maintain a brake from braking position, and a brake upon said lever and adapted to engage said fast pulley. 95

5. Stopping mechanism for knitting machines comprising in combination, a shaft having fast and loose pulleys thereon, a rock shaft having two positions only, namely a machine running position and a machine stopping position, a spring tending normally to move said rock shaft into machine stopping position, shipping means caused to function by rocking movement of said shaft into machine stopping position, thread fault detecting means, and connections therefrom to restrain said rock shaft from rocking movement into machine stopping position, but permitting said shaft so to rock upon the occurrence of thread fault, a cam of relatively short radius and fast upon said rock shaft, a lever mounted upon the machine framing, and a brake upon said lever and adapted to engage the fast pulley upon the operation of the shipping means, said lever being adapted to be directly acted upon by said cam. 100 105 110 115

6. Stopping mechanism for knitting machines comprising in combination, a shaft having fast and loose pulleys thereon, a rock shaft having two positions only, namely, machine running position and machine stopping position, a spring tending normally to move said rock shaft into machine stopping position, shipping means caused to function by rocking movement of said shaft into machine stopping position, thread fault detecting means, and connections therefrom to restrain said rock shaft from rocking 120 125 130

movement into machine stopping position but permitting said shaft so to rock upon the occurrence of thread fault, a cam upon said rock shaft, a lever upon a fixed part of the machine, yielding means to keep the said lever in constant contact with said cam during the running of the machine, and a brake carried by said lever and adapted through the

action of said yielding means to be moved into engagement with the fast pulley upon the actuation of the stopping means by movement of the rock shaft.

In testimony whereof, I have signed my name to this specification.

EDSON S. HINELINE.
